UNITED STATES PATENT OFFICE.

CHARLES E. BISER, OF SELMA, ALABAMA.

TWO-CYCLE UPRIGHT GAS-ENGINE.

1,383,518.

Specification of Letters Patent.

Patented July 5, 1921.

Application filed March 10, 1919. Serial No. 281,657.

To all whom it may concern:

Be it known that I, CHARLES E. BISER, a citizen of the United States, residing at Selma, in the county of Dallas and State 5 of Alabama, have invented certain new and useful Improvements in Two-Cycle Upright Gas-Engines; and I do declare the following to be a full, clear, and exact description of the invention, such as will enable others 10 skilled in the art to which it appertains to make and use the same.

This invention relates to internal combustion engines, and it relates more specifically to a two-cycle upright gas engine, of 15 improved construction.

One object of this invention is to provide an improved gas engine in which the combustible mixture is pre-heated and minimizes the heating and consequent expansion 20 of the piston-head.

Another object is to provide an engine of improved construction in which the combustible mixture is compressed within the hollow piston, out of contact with the body 25 of lubricating oil and out of the oil-mist that exists where a splash oiling system is employed.

Another object is to provide an improved internal combustion engine in which the cylinder, cranks and piston-pivots are entirely inclosed in an oil-chamber, so as to 30 provide for thoroughly and automatically lubricating the working parts with maximum efficiency and minimum consumption 35 of oil.

Another object is to provide an improved construction in which the lower cylinder head and upper part of the crank-housing are cast integrally, and the engine base and 40 lower part of the oil chamber are cast integrally, so as to minimize the number of castings and to minimize the number of operations in constructing and assembling the parts, thereby generally reducing the cost 45 of manufacture; also providing maximum rigidity, solidity and strength.

Other objects and advantages may become 50 apparent to persons who read the following details of description in connection with the accompanying drawings, in which:

Figure 1 is a vertical sectional view, the section being taken in the axial plane of the crank-shaft and piston-head-pivots; and

Fig. 2 is a vertical sectional view substantially along the line 2-2 of Fig. 1.

Referring to these drawings in detail, the engine comprises a base section 5, an intermediate section 6, an upper main section 7, a cap section or upper cylinder head 8, a piston head 9, connecting rods 10, a piston 60 pin 11, a crank-shaft 12 and other minor elements which will be hereinafter specified.

The sections, 5, 6, 7 and 8 are secured together in superposed relation, the surfaces at which these elements are joined, being 65 plane and horizontal, so that the operations of forming and assembling these sections or castings are reduced to the minimum and the cost of manufacture is proportionately reduced. The joints between the castings 70 are suitably packed to render them fluid-tight, and suitable bolts or other fastening means are employed for securing the castings together so as to form a unitary body which is rigid and strong, and which comprises a casing or outwardly sealed chamber 75 in which the piston head, cranks and connecting-rods are inclosed and protected from dust and other detrimental agencies. The sections 5 and 6 combine to form a hollow 80 body comprising the lower cylinder head, the crank-shaft-housing and the oil-basin, and this hollow body combines with the chambers 18 to form the outwardly sealed chamber previously mentioned.

The base section 5 is in the form of a basin which holds oil for lubricating the engine as hereinafter described, and crank shaft supports 13 and 14 are cast integrally with this section. Each crank shaft support 90 14 is spaced from the corresponding crank shaft support 13 to provide room for the cranks 15 to rotate, and the connecting rods 10 are journaled respectively on the cranks 15 and have their upper ends journaled on 95 the ends of the piston pin 11. The middle portion of the piston pin extends diametrically through the middle portion of the piston head 9, while the portions of the piston pin between its middle and end portions extend through slots 16 in the cylinder 100 17. The slots 16 are diametrically opposite and axially parallel, and each slot 16 is sufficiently wide to avoid contact with the piston pin 11, so that the sides of these slots 105 need not be accurately milled or machined, the purpose of these slots being to provide clearance for the piston pin 11 and to admit oil from the passages which are formed by chambers 18 of the upper main section, and 110

openings 19 through the intermediate section, the latter being in open communication with the oil basin and with the chambers 18.

The intermediate section 6 is united with 5 the lower section 5 in a horizontal plane communicating with the axis of the crank shaft 12, and the upper middle portion 20 of this section constitutes the lower cylinder head which closes the lower end of the cylinder 17. This cylinder head is apertured at 10 21 to provide an outlet port which communicates with or forms part of a bypass 22 in the wall of the cylinder 17, said bypass having its outlet into the upper portion of the cylinder 15 at a point immediately above the closed upper end of the piston head when the latter is in its lowermost position. The outlet or exhaust port 23 is diametrically opposite the upper end of the bypass 22, and a 20 guard or shield 24 is formed on the upper end of the piston head to prevent a direct passage of the combustible mixture from the bypass to and through the exhaust port. This shield 24 is preferably upwardly and outwardly curved for the purpose of preventing the lubricating oil from passing beyond this guard so that the loss of oil is prevented, the detrimental effects of oil in the cylinder is eliminated and the oil is applied to the 30 exterior convexed surface of the piston head. In the upper portion of the intermediate section 6 is formed the inlet passage 25 which conducts combustible gas from the carburetor 26 through a check valve 26' into 35 the lower part of the cylinder 17.

The lubricating oil is conducted from the bottom section into the upper part of the upper main section through the medium of pipes or oil ducts 27, and the oil drips or 40 pours from the pipes 27 onto the upper ends of the connecting rods 10. These connecting rods may be cut away at 28 to provide inwardly inclined surfaces which direct the oil into the slots 16, so that the piston head 45 is continually lubricated through these slots. Moreover, the oil is directed by the cut-away inclined portions 28 onto the piston-head pivots or ends of the piston pin 11. The oil flows from the upper ends of the connecting 50 rod 10 down through the chamber 18, opening 19 and onto the cranks or wrist pins 15, and drips or flows from the cylinder 17 to the bearing of the crank shaft. This obviates the necessity for having the cranks dip 55 into the oil in the lower section, and if desired, the oil may be kept at a level below the cranks 15, so that splashing and the consequent retarding of the crank shaft is avoided.

60 In order that oil may be caused to circulate from the lower section to the upper part of the upper main section, as described in the foregoing, any appropriate pumping system or device may be employed, and I 65 have indicated at 29 a pump which is oper-

ated by means of an eccentric 30 on the crank shaft, said pump being operatively connected with the oil ducts or pipes 27.

In operation, the upward movement of the piston head draws combustible fluid through 70 the inlet 25 and valve 26' into the cylinder 17, at the same time compressing the previous charge in the upper portion of the cylinder 17; when the explosion takes place, the piston head is forced downward, thereby 75 compressing a charge of fluid within the piston-head and bypass 22, at the same time warming the charge within the piston head and cooling the latter; and when the piston head has reached its lowermost position, the 80 compressed charge passes through the passages 21—22 into the upper part of the cylinders immediately to be compressed with the next upward movement of the piston.

Although I have described this embodiment of my invention very specifically, it is understood that my invention is not limited to these exact details of construction, and that I may make changes within the scope of the inventive idea disclosed in the foregoing description and following claims.

I claim:

1. An upright internal combustion engine comprising lower and intermediate and upper main sections superposed and joined 95 to one another by substantially horizontal surfaces, the lower section comprising crank-shaft supports, the intermediate section comprising passages and also comprising the lower cylinder-head between said passages, 100 the upper main section comprising chambers and a cylinder between the chambers, said chambers registering with said passages of the intermediate section, said cylinder being formed with slots through which 105 the interior of the cylinder communicates with said chambers, a piston head in said cylinder and provided with pivots extending through said slots into said chambers, a crank-shaft supported by said lower section, 110 and connecting-rods pivoted to said pivots and crank shaft.

2. An upright internal combustion engine comprising lower, intermediate and upper main sections superposed and joined to one 115 another by plane horizontal surfaces, the lower section being formed of an integral casting and comprising an oil-basin and crank-shaft supports, the intermediate section being formed of an integral casting and 120 comprising passages in open communication with said oil basin and also comprising the lower cylinder head between said passages, the upper main section being formed of an integral casting and comprising chambers 125 and a cylinder between the chambers, said chambers registering with said passages of the intermediate section, said cylinder being formed with diametrically opposite axially parallel slots through which the interior of 130

the cylinder communicates with said chambers, a piston-head in said cylinder and provided with pivots extending through said slots into said chambers, a crank-shaft supported by said lower section, and connecting-rods pivoted to said pivots and crank shaft.

3. An upright internal combustion engine comprising lower and intermediate and upper main sections superposed and joined to one another, the lower section comprising an oil-basin and crank-shaft supports, the intermediate section comprising passages in open communication with said oil basin and also comprising the lower cylinder head between said passages, the upper main section comprising chambers and a cylinder between the chambers, said chambers registering with said passages of the intermediate sec-

tion, said cylinder being formed with diametrically opposite axially parallel slots through which the interior of the cylinder communicates with said chambers, a piston head in said cylinder and provided with pivots extending through said slots into said chambers, a crank-shaft supported by said lower section, connecting-rods pivoted to said pivots and crank shaft, and means operable by the engine to take oil from said basin of the lower section and apply it in the upper end of said chambers at points adjacent to said slots so that oil will pass through the slots to the piston head and thence gravitate through said chamber and passage to said basin.

In testimony whereof I have hereunto set my hand.

CHARLES E. BISER.
